UNITED STATES PATENT OFFICE

124,247

DESIGN FOR A BUTTON

Curtis W. Dawson, Kansas City, Mo., assignor to
Universal Button Fastening & Button Com-
pany, Detroit, Mich., a corporation of Michi-
gan

Application August 30, 1940, Serial No. 94,731

Term of patent 14 years

To all whom it may concern:

Be it known that I, Curtis W. Dawson, a citizen of the United States, residing at Kansas City, in the county of Jackson and State of Missouri, have invented a new, original, and ornamental Design for Buttons, reference being had to the accompanying drawing, forming a part thereof.

In the drawing:

Figure 1 is a plan view of the ornamental button; and

Fig. 2 is a transverse section thereof, showing

the contour of the central depression in the button.

The characteristic feature of my design is the central depression in the button top embracing the thread holes and of such shape and contour as to minimize the relatively large portion of the button top devoted to thread holes.

I claim:

The ornamental design for a button, as shown and described.

CURTIS W. DAWSON.
